UNITED STATES PATENT OFFICE.

JAMES S. FORD, OF CHICAGO, ILLINOIS, ASSIGNOR TO AMERICAN TELEPHONE AND TELEGRAPH COMPANY, A CORPORATION OF NEW YORK.

WIRE-CONNECTOR.

SPECIFICATION forming part of Letters Patent No. 748,716, dated January 5, 1904.

Application filed October 9, 1903. Serial No. 176,383. (No model.)

To all whom it may concern:

Be it known that I, JAMES S. FORD, residing at Chicago, in the county of Cook and State of Illinois, have invented certain Improvements in Wire-Connectors, of which the following is a specification.

This invention relates to wire-connectors and may be employed to effectively unite wires or rods, thereby making them electrically and mechanically continuous, to serve as a terminal attachment for such wires, and to connect wires with apparatus of any kind or with voltaic batteries.

The connecting device is adapted to be applied to and released from wires with great celerity and ease, is of quite low cost, and may with equal facility be employed to unite wires of the same size or diameter or wires of different sizes, and in the latter case is particularly convenient, since by it wires of different sizes may be clamped without reversing the parts of the device or in any way altering the adjustment thereof.

The device of my invention while designed mainly as a connector for wires employed as conductors in telegraphic, telephonic, or other electrical systems, in which case it becomes itself a portion of the electrical circuit, is also well adapted for use as a clamp or connector for wires employed mechanically, as in the construction of wire fences or wirework in general, and in either capacity is most convenient.

The device is composed of a tubular member having an opening on one side for the reception of the wires and an inner jaw on each side of the opening with a plate within the tube and freely movable therein whose edges extend over the jaws and having a screw threaded in the tubular member adapted to press the plate toward the jaws and clamp in them any wires or rods that it is desired to connect together. The tubular member is preferably of a rectangular cross-section, although this is not necessary.

Reference is made to the accompanying drawings, in which—

Figure 1 is a side elevation of the invention. Fig. 2 is a plan view. Fig. 3 is a sec-

tion on line x x of Fig. 1, and Fig. 4 is a section on line y y of Fig. 3.

In the several figures of the drawings, a represents a tubular member of the clamp or connector, rectangular in cross-section and composed of the upper part 1, from which extend the side pieces 2, 2, each terminating with an inward extension 3, whose inner surface inclines toward the inner surface of the side piece at an obtuse angle to form a wire-holding jaw 7. The opening between the jaws 60 is of sufficient width for any sized wire that the clamp is designed for. At each open end of the tube a and central thereof is a pendant or finger 5, preferably integral with the said tube and shorter than the side pieces 2, 65 adapted to serve as a stop or abutment. A flat square plate d is inclosed within the tube a , the parts being so proportioned that it can be easily inserted and withdrawn. It is slightly narrower than the width of the tube- 70 channel and shorter than the distance between the stops 5 5, so that it may have a free and unobstructed movement, as represented in Figs. 3 and 4. A screw b , having a slotted head and a rounded point 6, engages with a 75 thread 4, cut in the part 1 of the tube a , and has a jam-nut c to hold it firmly in place when it is pressing upon the plate d .

When the clamp or connector is not in use, the screw may be turned inward to hold the 80 plate against the jaws 7 7; but when it is to be used the screw is turned outward and the plate pressed against its end until sufficient space is made for the reception of the wires w w^2 between the plate and the jaws 7 7, 85 which are passed through the opening to the jaws. Then the screw is turned inward hard upon the plate, whose opposite and parallel edges are forced upon the wires and hold them securely in the jaws. The jam-nut is 90 then screwed down upon the face of the part 1 and locks the screw in place. The plate being free in its movement readily adapts itself to clamp-wires of the same size or wires of different sizes in the jaws 7 7, and Fig. 3 95 represents a large and a smaller wire clamped in the jaws, the plate being inclined upon each wire. The screw end bearing upon the

central part of the plate forces the same downward whether it is on a level or inclined. This clamp is equally serviceable for holding wires of round, square, or any other cross-section.

5 I claim—

1. A wire-connecting device or clamp comprising a tubular member having an opening in one side and a jaw on each side of the opening, a movable plate within the tubular member extending over the jaws, and means for applying pressure upon the plate to move it toward the jaws.
- 10 2. A wire-connecting device or clamp comprising a tubular member having an opening in one side and an elongated jaw at each side of the opening, a movable plate within the tubular member extending over the jaws, and means for applying pressure upon the plate to move it toward the jaws.
- 15 3. A wire-connecting device or clamp comprising a tubular member having an opening on one side and an integrally-formed elongated jaw on each side of the opening, a movable plate within the tubular member extending over the jaws, and means for applying pressure upon the plate to move it toward the jaws.
- 20 4. The herein-described connecting device composed of a tubular member having an opening on one side, and a jaw on each side of the opening, a plate within the tube having edges extending over the jaws, and a screw threaded into the tubular member whose point is adapted to bear upon the plate and press the same toward the jaws.
- 25
- 30
- 35

5. A connecting device comprising a tubular member having a horizontal opening on one side and a wire-holding jaw on each side of the opening, a stop at each open end of the tube, a plate within the tube having opposite edges extending over the jaws, and a screw threaded into the tube opposite said opening, whose point is adapted to bear upon the plate, substantially as described.

40 6. In a wire clamp or connector, the combination of a tubular member square in cross-section having a horizontal opening on one side and a wire-holding jaw on each side of the opening and a stop at each end of the tube, a plate within the tube having opposite edges covering the jaws, and a screw threaded into the tube opposite said opening whose point is adapted to bear upon the plate.

45 7. In a wire clamp or connector, the combination of a tubular member rectangular in cross-section having a horizontal opening on one side and a wire-holding jaw on each side of the opening and a pendant-stop at each end of the tube, a square plate within the tube 50 having opposite parallel edges covering the jaws and a screw threaded into the tube central therewith and over said opening whose point is adapted to bear upon the plates.

55 In testimony whereof I have signed my name to this specification, in the presence of two subscribing witnesses, this 8th day of September, 1903.

JAMES S. FORD.
